UNITED STATES PATENT OFFICE.

GEORGE W. DRAPER, OF BRISTOL, CONNECTICUT.

HEADLIGHT.

Application filed April 6, 1925. Serial No. 21,105.

This invention relates to improvements in head lamps for motor driven vehicles such as shown in the application filed by me December 26, 1924 and bearing the Serial No. 758,237.

An object of the present invention is to improve and simplify certain features of the lamp disclosed in the application above noted and to this end provides novel means for mounting and securing a reflector within the lamp casing, the said means acting to also retain a deflector plate and apron so that the latter together with the reflector may be securely held in place by the lens retaining means of the lamp, the construction permitting of ease in assembling and providing an efficient non-rattling head lamp.

Another object of the invention is the provision of a lamp which includes a novel lens holding and casing closing door, together with novel means for securely holding the door in closed position.

With the above and other objects in view, the invention further includes the following novel features and details of construction, to be hereinafter more fully described, illustrated in the accompanying drawings and pointed out in the appended claims.

In the drawings:—

Figure 1 is a front elevation of a head lamp constructed in accordance with the invention.

Figure 2 is a section on the line 2—2 of

Figure 1.

Figure 3 is a section taken substantially on the line 3—3 of Figure 2, the section being on a reduced scale.

Figure 4 is an elevation of the lamp lining removed from the casing.

Figure 5 is a front elevation showing a modified form of the invention.

Figure 6 is a fragmentary side view of the form of the invention shown in Figure 5.

Figure 7 is an enlarged fragmentary section taken substantially on the line 7—7 of Figure 6.

Referring to the drawings in detail where in like characters of reference denote corresponding parts, the reference character 10 indicates a lamp casing which may be made of any suitable material and which may be cylindrical as shown in Figures 1 to 4 of the drawings, or of a rectangular form as shown in Figures 5 and 6. This casing has

its front provided with a lens 11 and the latter may be held in place by any suitable means, such for example as a ring 12 which carries a gasket 13 for contact with the outer face of the lens 11. Retaining screws 14 may be utilized to securely hold the ring in place.

Located within the casing 10 is a reflector 15, the latter extending from the top of the casing adjacent the rear wall thereof, downwardly and forwardly to the forward lower edge of the casing so as to provide a concave reflecting surface. The rear edge of the reflector 15 bears against a stop or flange 16 secured within the casing and has its lower edge provided with a downwardly extending tongue 17 which enters a groove provided in the block 18, the latter being rigid with the bottom of the casing. This block may be provided with a threaded socket to receive one of the retaining screws 14.

Bearing against the front edge of the reflector 15 is a lining 19. This lining is shaped to conform to the shape of the casing and its rear edge conforms to the shape of the reflector 15 with which it engages. This reflector engaging edge of the lining is rolled or provided with a reinforcing wire 20. Extending across the forward upper edge of the lining 19 is an apron 21. This apron extends downward for an appreciable distance and has its lower edge connected to the top of the lining by an upwardly extending rearwardly curved plate 22. The plate 22 and apron 21 are located in front of and extend behind a lamp 23. This lamp is carried by a lamp socket 24 which extends through the reflector 15 and may receive its current through a conductor wire 25 which extends through an insulated bushing 26.

Extending around the edge of the lining 19 and across the lower edge of the apron 21 is a compressible gasket 27, the said gasket bearing against the inner face of the lens 11.

In assembling the lamp, the reflector is placed in position and the lining 19, apron 21 and plate 22 which are constructed as a unit, are placed within the casing against the reflector. The lens is then secured in place by the ring 12, the lens bearing against the gasket 27 and forcing the lining 19 inward against the reflector so that the parts are securely held in place and objectionable rattling prevented.

If desired the casing may be substantially in form as illustrated in Figures 5 and 6 of

the drawings and the lens 11' may be carried by a door 28. This door has extending from its opposite side edges flanges 29 and 30, the first mentioned flange being hinged to the casing by means of a hinge 31. The flange 30 is provided with an opening for the passage of the shank of a hook 32, the inner end of which engages over a lug 33 extending from the casing 10'. The outer end of the hook has threaded thereon a binding nut 34 which bears against the flange 30 so as to removably hold the door in closed position. The door is provided with an opening 25 for the passage of the rays of light and the upper edge of this opening is disposed below the lamp within the casing so that the light opening in this form of the invention as well as in the form previously described is arranged below the lamp and at the lower part of the casing.

The invention is susceptible of various changes in its form, proportions and minor details of construction and the right is herein reserved to make such changes as properly fall within the scope of the appended claims.

Having described the invention what is claimed is:—

1. A head lamp comprising a casing, a lens therefor, a retaining ring including a segmental portion disposed in advance of and extending an appreciable distance downwardly on the lens, a curved reflector, a lining formed in one piece to conform to the shape of the casing and said reflector and

positioned forwardly of said reflector, said lining including an apron depending from the forward edge thereof and terminating in a plane with the lower edge of the segmental portion of the ring, and arranged at the opposite side of the lens, a curved plate connecting the apron with the upper portion of the lining, and an electric light bulb supported by the reflector and directly behind said plate.

2. A head lamp comprising a casing, a lens therefor, a block secured to the bottom of the casing and arranged within the latter directly behind said lens, a retaining ring for the lens embracing said casing, said block having a groove in its upper surface, a fastening element securing the ring to the lower portion of the block, a curved reflector arranged within the casing, and including a flange adapted to be received by said groove, a stop plan depending from the upper portion of the casing and against which the adjacent end of the reflector engages, a lining shaped to conform to the casing and reflector, and having its lower end positioned between the block and the lens, an apron carried by the lining and depending therefrom to cover an appreciable portion of the upper part of said lens, a curved plate supported by the lining and said apron, and an electric light bulb supported by the reflector directly behind said curved plate.

In testimony whereof I affix my signature.
GEORGE W. DRAPER.
